(57) **CLAIM**

We claim the ornamental design for a fluid dispenser, as shown and described.

DESCRIPTION

FIG. 1 is a perspective view of a fluid dispenser constructed in accordance with one embodiment of the present invention, wherein the fluid dispenser includes a bracket, a bottle, and a cover;

FIG. 2 is a front view of the fluid dispenser shown in FIG. 1; FIG. 3 is a rear view of the fluid dispenser shown in FIGS. 1 and 2;

FIG. 4 is a top view of the fluid dispenser shown in FIGS. 1-3; FIG. 5 is a bottom view of the fluid dispenser shown in FIGS. 1-4;

FIG. 6 is a left side view of the fluid dispenser shown in FIGS. 1-5;

FIG. 7 is a right side view of the fluid dispenser shown in FIGS. 1-6;

FIG. 8 is a perspective view of an alternative embodiment of a fluid dispenser according to the present invention, wherein the fluid dispenser includes a bracket and a bottle;

FIG. 9 is a front view of the embodiment of the fluid dispenser shown in FIG. 8;

FIG. 10 is a rear view of the embodiment of the fluid dispenser shown in FIGS. 8 and 9;

FIG. 11 is a top view of the embodiment of the fluid dispenser shown in FIGS. 8-10;

FIG. 12 is a bottom view of the embodiment of the fluid dispenser shown in FIGS. 8-11;

FIG. 13 is a left side view of the embodiment of the fluid dispenser shown in FIGS. 8-12; and,

FIG. 14 is a right side view of the embodiment of the fluid dispenser shown in FIGS. 8-13.

The broken-line disclosure in the views is understood to represent portions of the article in which the claimed design is embodied, but which for no part of the claimed design.
